GARMENT HANGER SLEEVE HOLDER

James M. Hershberger, Hillsboro, Ind.

Application November 15, 1951, Serial No. 256,495

1 Claim. (Cl. 223—74)

1

This invention relates to a garment hanger to which are applied sleeve holders in such manner that the holders may be inserted through the sleeves of the garment, such as a coat, and these holders will hold the sleeves in an extended, flat condition so as to avoid wrinkling or massing while the garment is hanging on the hanger.

The invention is incorporated preferably with the common and well known wire type of hanger, although other types may be employed equally as well. To the hanger there is freely, rockably attached a holder for each sleeve, the holder normally hanging vertically downwardly from the hanger so that the weight of the holder will normally tend to hold the sleeves in a downwardly extending position in reference to the hanger. The sleeve holders are made to be both extensible longitudinally and laterally so that the holders may be accommodated to varying sizes and lengths of sleeves all in a very simple manner.

With the holders supported by the ordinary wire hanger, these holders are provided with a loop in each instance, forming an eye, so that the wire of the hanger may be carried through the eye and the holder may be moved across the transverse bar provided on the wire hanger and also carried up around the ends so that the holder may be freely entered into the sleeve of the garment through the arm holes all without having to stretch the garment, or otherwise go through any bending actions or like manipulations of the hanger or of the holders. A further advantage of the invention resides in the extreme simplicity of the invention achieving the above indicated results all in a form which may be produced at a low cost of production.

The invention is described in reference to the accompanying drawing, in which:

Fig. 1 is a view in side elevation of a hanger to which the invention is applied;

Fig. 2 is a view in side elevation of a sleeve holder; and

Fig. 3 is a view in transverse section on the line 3—3 in Fig. 2, on an enlarged scale.

A garment hanger of any of the well known forms, made out of wire, is herein shown as being formed from a single length of wire to have a hanger hook 10 from which the wire extends through a shank 11 to continue downwardly and outwardly through an inclined length 12 which normally serves to pass under the shoulder portion of the garment, and from this length 12 the wire is carried around through a curved end portion 13, thence through a straight transverse length 14, back around upwardly through the

2

bend 15 into the upwardly inclined length 16 and thence finally upwardly into a length 17 which is twisted around the shank 11 to fix that end 17 in position, and complete the shape of the hanger, the hanger being generally designated by the numeral 18.

There are two sleeve holders designated generally by the numerals 19 and 20 provided to swing freely from the transverse length 14 of the hanger 18. Since each of these holders 19 and 20 are identical in shape and size, the description of the one holder 19 will be sufficient to describe both holders 19 and 20. Referring to Fig. 2, a length of wire is formed into a general wishbone shape to have the two legs 21 and 22 curving outwardly and downwardly from an upper eye 23 which is formed by making one complete turn of the wire through the bend 24 to have the ends of wires extend around and downwardly into the leg portions 21 and 22.

Two L-shaped wire members 25 and 26 are formed and the respective legs 27 and 28 are carried upwardly along the lower end portions 29 and 30 of the legs 21 and 22 respectively. The leg 27 and the portion 29 are interengaged by means of any suitable clamp, herein shown as a U-shaped band 31 straddling the two members 27 and 29 to be squeezed thereagainst by means of a thumb screw 32, Fig. 3.

In like manner, the leg 28 and the portion 30 are adjustably interengaged by means of a clamp 33 and the thumb screw 34 formed in identically the same manner as the members 31 and 32 as illustrated in Fig. 3. The lower legs 35 and 36 of the two L members 25 and 26 extend one along the other, Fig. 2, and are adjustably interengaged by a clamp 37 passing over the two legs 35 and 36 and clamped thereagainst by means of the thumb screw 38, the clamps 31, 33, and 37 being identical in shape and size.

In forming the hanger 18, before the end 17 is twisted around the shank 11, the two holders 19 and 20 have the bar 14 passed through their eyes 23 so that the holders 19 and 20 hang freely from that bar 14 and may be shifted from one end to the other and likewise are free to revolve around that length 14, only within the limits of the inclined members 12 and 16.

In using the device, the holders 19 and 20 are inserted through the armholes of the garment and allowed to extend downwardly through the sleeves, and the garment is pulled upwardly and around over the lengths 12 and 16 of the hanger 18. The holders 19 and 20 may be readily adjusted to conform to the width and length of

the sleeves by reaching up through the cuffs and loosening and tightening the clamps 31, 33, and 37 so as to secure the desired overall length of the holder 19 or 20 as the case may be, or both, and also the clamp 37 may be loosened and tightened to allow the holder to be expanded or retracted laterally by allowing the legs 35 and 36 to slide one past the other through the clamp 37 to be ultimately secured in position by the thumb screw 38. In other words, the holders 19 and 20 are both longitudinally extensible and also laterally extensible.

While I have herein shown and described my invention in the one particular form, it is obvious that structural changes may be employed without departing from the spirit of the invention, and I therefore do not desire to be limited to that precise form beyond the limitations which may be imposed by the following claim.

I claim:

For use with a garment hanger, a sleeve holder comprising a wishbone-shaped frame composed of a pair of elastic wire members; a centrally disposed upper end eye portion; said wire mem-

bers being fixed by upper portions one to the other through said eye portion; and a lower U-shaped member having a transverse web portion from the ends of which legs extend upwardly respectively along lower end portions of said wire members; means adjustably securing said leg members along said wire members; said web being in two overlapping parts; and means interengaging said web parts whereby said legs and the connected wire members may be variably spaced apart.

JAMES M. HERSHBERGER.
